UNITED STATES PATENT OFFICE.

FRANK HARDING, OF SAN DIEGO, CALIFORNIA.

COMBINATION-RETAINER.

1,136,331.

Specification of Letters Patent. Patented Apr. 20, 1915.

Application filed June 13, 1912. Serial No. 703,413.

To all whom it may concern:

Be it known that I, FRANK HARDING, a citizen of the United States, and a resident of San Diego, in the county of San Diego and State of California, have invented certain new and useful Improvements in Combination-Retainers, of which the following is a specification.

My invention relates to a retainer or receptacle mounted on the backs of seats and the like, and it is for the purpose of holding books, hats, cards, envelops, pencils, communion glasses, etc., and the objects of my invention are, first, to provide a retainer of this class which possesses all of these essentials, second, to provide a retainer of this class that is simple of construction, easily installed and in which some of the parts are folded when not in use, and third, to provide a retainer of this class that is so mounted that it may be easily kept clean.

With these and other objects in view as will appear, my invention consists of certain novel features of construction, combination and arrangement of parts as will be hereinafter described in detail and particularly set forth in the appended claims,—reference being had to the accompanying drawings, and to the characters of reference thereon, which form a part of this specification, in which:—

Figure 1 is a perspective view of my retainer complete, showing by dotted lines the position of the hat holding part, when in position for use, Fig. 2 is a perspective view showing, in detail, the construction of the hat holding part of my device, and Fig. 3 is an elevational view on a smaller scale of my retainer complete, shown mounted on the back of a seat.

Similar characters of reference refer to similar parts throughout the several views.

The book holder 1, hat holder 2, card receptacle 3, glass holder 4 and pencil holder 5 constitute the principal parts of my retainer.

The book holder 1 is shaped as shown best in Fig. 1 and is preferably made of woven wire, and is rectangular in shape, leaving the top and the side next to the back of the seat open. At the top at each end next to the seat-back is provided an extended lug 1^a which is adapted to be inserted into an eye-bolt 1^b in the back of the seat, which provides a pivotal mounting for the retainer.

On the lower wire next to the seat-back is

provided a number of small pieces of rubber 1^c, adapted for cushions between the lower portion of the retainer and the back of the seat.

On the bottom of the retainer at its one end, is rigidly mounted a box 2^a preferably made of metal, and shaped as shown best in Fig. 2. It is provided at its one end with an open, downwardly extending portion 2^b. In this box is mounted the hat holder 2 which is a small rod bent at right angles at 2^c, and the extended end thereof is adapted to reciprocate therein. Outside of the box the hat holder is also bent at right angles in a direction at right angles to the extended end, and extending therefrom some distance it is provided with a loop on its free end over which the crown of a hat may be placed. The box 2^a is so constructed that when the rod is pushed in, so that its extended end 2^c is against the inner end of the box, the holder may be turned into the position as shown by the dotted lines in Fig. 2, which allows it to take a horizontal position as shown best in Fig. 1.

On the top side wire of the book holder 1 is pivotally mounted the glass holder 4 preferably made of wire and shaped as shown best in Fig. 1, suitable for receiving a plurality of glasses for communion purposes and the like, and adjacent thereto is provided a pin 4^a reciprocally mounted in the loop pieces 1^d, which is for the purpose of holding the glass holder 4 in a horizontal position when it is in use, and to allow it to drop down in a vertical position, out of the way, when not in use, by simply shifting the pin.

On the one end of the book holder 1 is rigidly mounted a small cylindrically shaped piece 5 converging toward its lower end and adapted for a pencil.

Though I have shown and described a particular construction and arrangement of parts, I do not wish to be limited to this particular construction and arrangement, but desire to include in the purview of my invention, the construction and arrangement substantially as set forth in the appended claims.

It is obvious that with this construction and arrangement there is provided a combination retainer for the backs of seats and the like, adapted for holding hats, books, cards, pencils, envelops, communion glasses and the like; that is simple of construction,

easily installed and durable; that it will not deface the seat upon which it is placed; that the parts are readily folded into a very compact form when not in use; that it may 5 be readily removed if desired by simply springing the inner upper corners of the frame inwardly; that it being pivotally mounted allows it to be tilted for cleaning.

Having thus described my invention, what 10 I claim as new and desire to secure by Letters Patent is:—

1. In a device of the class described the combination of a rectangularly shaped box, a rod with a loop in one end and with a 15 short bend in its other end reciprocally mounted in said box adapted to be shifted therein to a position at right angles when in certain relative positions by reason of a slot in one end of said box.
- 20 2. In a device of the class described the combination of a rectangularly shaped box, provided with a slot in its one end, adapted to be secured to the back of a seat, a rod with a loop in one end adapted for a hat and with a 25 short bend in its end and a right angled bend intermediate thereto reciprocally

mounted in said box so that the short bend in the end thereof may extend out through said slot and allow said rod to be turned at right angles in said box when in certain position therein. 30

3. In a device of the class described the combination of a rectangularly shaped box inclosed throughout, adapted to be attached to the back of a seat with a right angled 35 extension on one end thereof with its side open and a rod with one end reciprocally mounted therein provided with a short right angled bend adapted to be held in certain position except when shifted to the end with the right angled bend, then it may be turned at right angles thereto, a loop adapted for a hat in its other end and a right angled bend intermediate between said loop and said short bend. 40 45

In testimony whereof, I have hereunto subscribed my name in the presence of two subscribing witnesses.

FRANK HARDING.
